CLAIM

We claim the ornamental design for a combination fireproof case and photo album with fireproof spine, as shown and described.

DESCRIPTION

FIG. 1 is a perspective view of a combination fireproof case and photo album with fireproof spine, embodying the design of the present invention;

FIG. 2 is a front elevational view thereof, the rear elevational view being identical thereto;

FIG. 3 is a left side elevational view thereof;

FIG. 4 is a right side elevational view thereof; and,

FIG. 5 is a top plan view thereof, the bottom plan view being identical thereto.
